CLAIM

The ornamental design for a fluid metering valve for medical apparatus and the like, substantially as shown and described.

DESCRIPTION

FIG. 1 is a perspective view of a metering valve for medical apparatus and the like illustrating our design;

FIG. 2 is a bottom plan view thereof;

FIG. 3 is a front elevation thereof;

FIG. 4 is a top plan view thereof;

FIG. 5 is a left side elevation thereof;

FIG. 6 is a right side elevation thereof; and

FIG. 7 is a rear elevation thereof.
